FLOW VALVE FOR OIL WELLS

Clarence H. Boring, New Straitsville, Ohio, assignor of one-half to Firmen Lambert, New Straitsville, Ohio

Application October 28, 1932. Serial No. 640,117

9 Claims. (Cl. 103—232)

This invention relates to flow valves for oil wells and has for its object to provide novel means whereby air, gas, or other fluid at low pressure may be utilized for lifting or elevating the fluid content of deep wells and thus minimize the expense and danger incident to present methods which use gas at high pressure for elevating the fluid.

Heretofore it has been the practice to introduce gas at high pressure into an annular chamber or space between the well casing and tubing in order to force the fluid at the bottom of said annular space upwardly through the tubing to the surface of the ground or other point of discharge. When the well is deep, very high gas pressure is required to effect the elevation of the fluid, which not only renders the installation and operation of the mechanism expensive but often endangers the safety and lives of the workmen. The present invention aims to obviate these objectionable features and to effect a conservation in gas and a reduction of the pressure of said gas or other fluid used for elevating purposes, by inserting within the well tubing a series of float controlled valves operable successively by the rise of the fluid in the tubing for controlling the admission of gas or other fluid into said tubing.

A further object is to so construct the valve casings and other associated parts that they will offer very little resistance to the upward passage of the liquid within the tubing and to provide a novel form of baffle beneath each valve casing which baffles also act as guides for the valve stems and thus insure positive closing of the valves.

A still further object of the invention is generally to improve this class of devices so as to increase their utility and efficiency.

In the accompanying drawings forming a part of this specification:

Figure 1 is a longitudinal sectional view, partly in elevation, of a conventional oil well showing the improved flow valves in position thereon.

Figure 2 is an enlarged longitudinal sectional view of one of the float valves and its associated parts, showing the valve in closed position.

Figure 3 is a similar view showing the valve in open position to admit gas into the well tubing.

Figure 4 is a transverse sectional view taken on the line 4—4 of Figure 2.

Figure 5 is a similar view taken on the line 5—5 of Figure 2.

Similar numerals of reference indicate corresponding parts in all the figures of the drawings.

The improved flow valve forming the subject

matter of the present invention is shown in connection with a conventional oil well in which 5 indicates the casing and 6 the inner tubing disposed therein and spaced therefrom to form an annular space or chamber 7 for the reception of gas, air, or other fluid at low pressure, said fluid being admitted into the chamber 7 through the top of the casing in any suitable or desired manner, as by a pipe 8. Interposed at spaced intervals in the length of the tubing 6 are pipe sections 9 of greater cross sectional diameter than the tubing 6 and connected with the tubing by tapered coupling sleeves 10 having their opposite ends threaded for engagement with corresponding threads on the tubing and adjacent pipe sections. The pipe sections 9 constitute protecting jackets for the float controlled valves and their associated parts which will be referred to more particularly hereinafter, and it will be understood that as many of the sections or jackets 9 may be used in a well as is found necessary or desirable. Secured to or formed integral with each pipe section 9 is an elbow 11 having a passage 12 formed therein, one end of which opens into the annular space or chamber 7 and the other end thereof into a valve cage 12'. The outer wall of each pipe section 9 is preferably formed with an annular series or row of projections 13 surrounding the entrance to the passage 12 and fitting over the end of the passage 12 and retained in position by the projections or lugs 13 is a screen 14 which prevents sediment and other impurities from entering the valve cage. Disposed within each pipe section 9 is a substantially elliptical-shaped casing 15 in which is mounted a correspondingly shaped float 16. The opposite ends of the casing 15 are provided with substantially conical-shaped caps 17 and 18 having threaded connection with the casing, as indicated at 19, so that the caps may be readily removed to facilitate cleaning the casings when necessary. The upper caps 17 are provided with a series of perforations 19 while the lower caps 18 are preferably formed with a single opening 20, the opening 20 permitting the liquid to enter the casing and the openings 19 permitting the liquid to discharge from the casing into the tubing. Disposed within the cage 12' is a ball valve 21 and immediately above the valve 21 is a valve stem 22, the lower end of which is provided with a head 23 which normally rests on the ball and serves to hold the valve in closed position. Arranged immediately below each casing 15 is a baffle 24 preferably conical in shape and secured in any suitable manner to the wall of the adjacent pipe section 9. The upper end of each baffle is 110

open while the lower end thereof is inclined downwardly and laterally so as to present a streamline effect and thus not offer any resistance to the flow of liquid within the tubing. The front wall of each baffle is provided with an opening 25 which serves to receive and guide a valve stem 22, the upper end of said stem passing through a similar opening 26 formed in the lower cap 18, with its terminal projecting within the adjacent casing 15 for engagement with the float 16. The lower reduced end of each baffle 24 is preferably provided with an opening 25 so as to permit the discharge of sediment or other foreign matter which may collect in the baffle. Each valve stem is provided with a stop collar 27 which, by engagement with the cap 18 of the valve casting, serves to limit the upward movement of said valve stem. It will here be noted that the elbow, baffle, and caps 17 and 18, are all inclined upwardly so as to present a streamline effect and thus not offer any resistance to the passage of liquid. When there is no liquid in the casings 15, the floats 16 will rest on the upper ends of the valve stems 22 and thus hold the valves in closed position so as to prevent the entrance of gas or other fluid from the annular space or chamber 7 into the well tubing. When, however, liquid enters any particular casing, the rise of the liquid therein will cause the float 16 to elevate, thus releasing the adjacent valve stem and permitting gas from the annular chamber 7 to enter through the passage 12 into the well tubing. The float 16, which is buoyed by oil or other liquid entering the casing 15 when the ungasified liquid is at a height sufficient in the tubing 9 so as to enter the casing 15, affords sufficient lifting force to clear the valve stem and permit unseating of the valve, but the float 16 will lose its lifting power when the supporting liquid becomes gasified by gas entering the tubing through a lower valve to the extent of its own weight less an equal volume of gasified liquid in which the float is immersed. In other words, the specific gravity of the float 16 is less than that of the liquid to be raised from the well and greater than the gasified flowing liquid. Preferably, the specific gravity of the float should be but little more than one-half that of the ungasified liquid to be lifted from the well. When ungasified liquid is in the tubing 6 and above the valve 21, the float 16 will be submerged and buoyed upward, thereby releasing the valve stem so as to permit opening of the valve. When gasified liquid is flowing upwardly in the tubing, the ungasified fluid will have dropped back out of the casing or float chamber 15 into the tubing through the opening 20 and be replaced with gasified liquid. Since the specific gravity of the gasified flowing liquid is reduced, the float 16 will not be supported by it and drops downwardly onto the valve stem to close the valve seat. In operation, gas, air, or other fluid at low pressure is introduced into the annular space 7 through the upper end of the well casing and passes downwardly within the space 7 to the bottom of the well to effect the lifting or elevation of the liquid within the tubing. Assuming the level of the liquid within the tubing has reached the height of the second valve casing 15, as indicated in Figure 3 of the drawings, the liquid in the tubing will elevate the two lowermost floats 16, thereby releasing the adjacent valve stems and permitting the gas from the annular space 7 to enter through the passages 12 and unseat the ball valves 21 so as to permit the

gas to escape within the tubing and elevate the liquid to the surface of the ground or other suitable point of discharge. During this operation, however, the upper valves will not be affected and remain closed until the liquid rises within the tubing and enters the upper casings 15 so as to release their valves. It will thus be seen that the valves are successively operated to control the admission of gas or other fluid into the well tubing and that the actuation of the valves depends upon the height of the liquid within the tubing. As the gas can only enter the tubing through the valves when the latter are open and depending upon the level of the liquid within the tubing, it follows that a conservation of gas is effected and that gas at a relatively low pressure may be utilized as the elevating medium so as not to endanger the lives or safety of the workmen. The streamlines of the baffle and its associated parts prevent excessive turbulence in the fluid, which results in what is known as cut oil, and also acts to prevent undue erosion of the parts by finely divided solids usually present in the fluid. Owing to the arrangement of the valves within the tubing the gas does not have to travel to the bottom of the tubing before starting its upward flight to effect elevation of the liquid, which is quite a desideratum, especially in the case of deep wells, as it not only permits the use of a relatively low pressure fluid but effects a conservation of the elevating medium.

As the valves are opened only when the level of the liquid reaches the float chambers, it follows that the gas or other fluid is excluded from the tubing above the liquid level therein, thus preventing loss of pressure in the annular space surrounding said tubing.

Having thus described the invention, what I claim is:

1. In an oil well, a casing, tubing disposed within the casing and spaced therefrom to form an annular chamber, means for introducing an elevating fluid within the chamber, a valve controlling the admission of fluid from the chamber into the tubing, and a float disposed within the tubing normally holding the valve closed and actuated by the rise of the liquid in said tubing to permit opening of said valve.

2. In an oil well, a casing, tubing disposed within the casing and spaced therefrom to form an annular chamber, means for introducing an elevating fluid into the chamber, valves controlling the admission of fluid from the chamber into the tubing and a plurality of floats disposed within the tubing and normally holding the valves closed and successively actuated by the rise of the liquid in the tubing to permit opening of said valves.

3. In an oil well, a casing, tubing disposed within the casing and spaced therefrom to form an annular chamber, means for introducing an elevating fluid into the chamber, valves for controlling the admission of fluid from the chamber into the tubing and a plurality of floats disposed within and arranged eccentric to the inner wall of the tubing and normally holding the valves closed, said valves being successively actuated by the rise of liquid in the tubing to permit opening of the valves.

4. In an oil well, a casing, tubing disposed within the casing and spaced therefrom to form an annular chamber, means for introducing an elevating fluid into the chamber, a pipe section forming a part of the tubing, a float chamber arranged within the pipe section, a valve for con-

- trolling the flow of fluid from the annular chamber into the tubing, and a float disposed within the float chamber and actuated by the rise of liquid in the pipe section to permit opening of the valve. 5
5. In an oil well, a casing and tubing spaced therefrom to form an annular chamber, means for introducing an elevating fluid into the chamber, a pipe section forming a part of the tubing, a float chamber arranged within the pipe section, a baffle arranged beneath the float chamber, a normally closed valve for controlling the flow of fluid from the annular chamber into the pipe section, a valve stem extending through the baffle into the float chamber, and a float operating within the float chamber and actuated by the rise of the liquid in the pipe section to release the valve stem and permit the entrance of the elevating fluid into said pipe section. 10
- 10 6. In an oil well, a casing and tubing spaced therefrom to form an annular chamber, means for introducing an elevating fluid into the chamber, a pipe section forming a part of the tubing, a float chamber having oppositely disposed conical head arranged within the pipe section, a substantially conical-shaped baffle arranged beneath the float chamber, an elbow secured to the pipe section and having a passage therein forming a source of communication between the annular chamber and the interior of the pipe section, a valve controlling flow of fluid through the passage, a valve stem resting on the valve and extending through the baffle into the float chamber, and a float disposed within said float chamber and actuated by the rise of the liquid in the tubing to release the valve. 15
- 15 7. In an oil well, a casing and tubing spaced therefrom to form an annular chamber, means for introducing elevating fluid into the chamber, a pipe section forming a part of the tubing, a float chamber disposed within the pipe section and arranged eccentric thereto, an elbow projecting inwardly from the pipe section and provided with a passage forming a source of communication between the annular chamber and the interior of the pipe section, a valve for controlling the flow of fluid through said passage, there being projections on the exterior wall of the pipe section around the entrance to said passage, a screen 20
- 20 8. In an oil well, a casing and tubing spaced therefrom to form an annular chamber, means for introducing elevating fluid into the chamber, a plurality of pipe sections of greater cross sectional diameter than the tubing interposed in the length thereof, a perforated float chamber disposed within each pipe section, a valve for controlling the flow of fluid from the annular chamber into each pipe section, and a vertically movable float operating in each float chamber and normally holding the adjacent valve closed, said floats being successively actuated by the rise of the liquid in the tubing to release the valves. 25
- 25 9. In an oil well, a casing and tubing spaced therefrom to form an annular chamber, means for introducing an elevating fluid into the chamber, a plurality of pipe sections of greater cross sectional diameter than the tubing interposed in the length thereof, a float chamber arranged within each pipe section and disposed eccentric to the inner wall thereof, each float chamber being provided with oppositely disposed tapered perforated heads, a baffle arranged beneath each float chamber and having spaced openings therein, one of which constitutes a guide opening and the other a drain opening, an elbow carried by each pipe section and having a passage therein 30
- 30 forming a source of communication between the annular chamber and the adjacent pipe section, a valve cage carried by each elbow, valves in said cages, valve stems normally holding the valves in closed position and extending through the guide 35 openings in the baffles into the adjacent float chambers, floats arranged within said chambers and actuated by the rise of the liquid in the tubing to permit release of the valves, and stop collars formed on the valve stems and adapted to engage 40 the float chambers for limiting the upward movement of said valve stems. 45
